UNITED STATES PATENT OFFICE.

JACOB NEWMAN AND LOUIS WEINBERG, OF PETERSBURG, VIRGINIA.

TRUNK ATTACHMENT.

SPECIFICATION forming part of Letters Patent No. 588,284, dated August 17, 1897.

Application filed September 9, 1896. Serial No. 605,275. (No model.)

To all whom it may concern:

Be it known that we, JACOB NEWMAN and LOUIS WEINBERG, citizens of the United States, residing at Petersburg, in the county 5 of Dinwiddie and State of Virginia, have invented certain new and useful Improvements in Trunk Attachments; and we do hereby declare the following to be a full, clear, and exact description of the invention, such as will 10 enable others skilled in the art to which it appertains to make and use the same.

Our invention relates to certain new and useful improvements in trunks, the object of the same being to provide an attachment 15 therefor by means of which the tray will be elevated simultaneously with the raising of the lid of the trunk, and be held at all times in a perfectly horizontal or level position.

The invention consists of a pair of tray- 20 supports located at each end of the trunk, links connecting said tray-supports with the usual ledge for supporting the tray, and connections between said tray-supports and the lid of the trunk whereby when the latter is 25 raised said supports will be elevated simultaneously, and held at all times in a horizontal position.

The invention also consists in other details of construction and combinations of parts 30 which will be hereinafter more fully described and claimed.

In the drawings forming part of this specification, Figure 1 represents a perspective view of a trunk constructed according to our invention, showing the lid of the same in its raised position with the tray resting upon its supports. Fig. 2 is a similar view of the same with the tray removed. Fig. 3 is a vertical cross-section of the trunk in its closed position with the tray removed. Fig. 4 is a perspective view, partly broken away, showing a modified form of the invention. Fig. 5 is a detail perspective view of one of the links connecting the tray-supports with the lid, as 45 shown in Fig. 4.

Like reference-numerals indicate like parts in the different views.

The trunk 1 is of the usual form and construction, having the lid 2 hinged thereto 50 and tray-supporting ledges 3 3 at each end thereof. Pivoted to the ledges 3 3 and extending upwardly therefrom are links 4 4 of

equal lengths and having pivotally connected to them at their upper ends the movable tray-supports 5 5, each consisting of a strip of 55 wood or metal L-shaped in cross-section with flanges or stops 6 6 at each end. These movable tray-supports 5 5 are connected to the inside of the lid or cover 2 by means of links 7 7, the same being provided with elongated 60 slots 8 8 therein, through which the securing bolt or screw 9 passes, providing for a small degree of lost motion, which is necessary when the lid 2 is closed. Adapted to rest upon the supports 5 5 is a tray 10 of ordinary construction, the same being held against displacement by the flanges or stops 6 6. 65

From the foregoing description it will be seen that when the lid 2 is elevated the movable supports 5 5, carrying the tray 10, will be 70 raised simultaneously, holding said tray at all times in a horizontal position. This permits of the ready removal of the contents of the body of the trunk 1 from the front side thereof. When the lid 2 is closed down upon 75 the trunk 1, the supports 5 5, carrying the tray 10, are also lowered, and when in their closed position they rest upon the top surface of the ledges 3 3. It will be observed, however, that the supports 5 will reach the ledges 3 before the lid 2 is entirely closed. In order, therefore, to permit the complete closure of the lid, the slots 8 8 in the links 7 are provided. 80

In the modified form of our invention illustrated in Figs. 4 and 5 we employ a peculiar 85 form of link for connecting the supports 5 5 with the lid 2. The said link is numbered 11 and differs from the links 7 in that it is formed with a T-shaped slot 12 at its upper end, having one portion thereof leading outwardly to 90 the side of said link, so that said link may be disconnected from the screw or bolt 9 when desired. When thus disconnected, there will be no movement of the supports 5 5 upon the raising or lowering of the lid 2. In this form 95 of the invention we also employ a stop for preventing the falling of the lid 2 when it has been raised to its open position. This stop consists of a pair of links or plates 13 14, one pivoted to the trunk 1 and the other to the 100 lid 2 and both being pivoted to one another at their outer ends.

From the foregoing description it will be seen that we have devised a simple, cheap,

and effective attachment for trunks, whereby the tray may be raised or lowered simultaneously with the opening or closing of the lid of the trunk, and whereby the same is held 5 at all times in a perfectly horizontal position.

Having now described our invention, what we claim as new, and desire to secure by Letters Patent, is—

1. The combination with a trunk having a lid or cover hinged thereto and ledges or supports at each end thereof, of movable tray supports located at each end of the trunk, a pair of links of equal lengths pivoted to each of said supports and to the adjacent ledge on 15 said trunk, and a link connecting each of said supports with said lid or cover having an elongated slot therein, through which its securing bolt or screw passes, substantially as and for the purpose described.
2. The combination with a trunk having a lid or cover hinged thereto and ledges or sup- 20

ports at each end thereof, of movable tray supports located at each end of the trunk, having flanges or stops at their outer ends, a pair of links of equal lengths pivoted to each of said supports and to the adjacent ledge on said trunk, and a link connecting each of said supports with said lid or cover having an elongated slot therein through which its securing bolt or screw passes, and a tray adapted to fit 25 upon said supports and to lie between said flanges or stops, substantially as and for the purpose described.

In testimony whereof we have signed this specification in the presence of two subscribers. 30

JACOB NEWMAN.
LOUIS WEINBERG.
